(57) **CLAIM**

The ornamental design for a chip, as shown and described.

DESCRIPTION

FIG. 1 is a perspective view of a chip showing our new design;

FIG. 2 is a top view thereof;

FIG. 3 is bottom view thereof;

FIG. 4 is a front view thereof;

FIG. 5 is a rear view thereof;

FIG. 6 is a left side view thereof; and,

FIG. 7 is a right side view thereof.

The broken lines depict environmental subject matter only and form no part of the claimed design.
